UNITED STATES PATENT OFFICE

JOHN M. WHELTON, OF PEABODY, AND ARTHUR F. PYM, OF SWAMPSCOTT, MASSACHUSETTS, ASSIGNORS TO UNITED SHOE MACHINERY CORPORATION, OF PATERSON, NEW JERSEY, A CORPORATION OF NEW JERSEY

MACHINE FOR EFFECTING RELATIVE MOVEMENTS BETWEEN SHOES AND THEIR LASTS

Application filed November 22, 1928, Serial No. 321,227. Renewed August 15, 1930.

This invention relates to machines for effecting relative movements between shoes and their lasts, and is herein illustrated as embodied in a machine in which such movement is effected by a roll acting against the counter portion of a shoe to pull the shoe from the last. For an example of a last pulling machine of this general type reference may be had to the copending application of Arthur Pym, Serial No. 458,163, filed April 2, 1921. It is to be understood, however, that in various novel and useful aspects the present invention is not limited to machines of the type shown in that application.

The machine disclosed in the above-mentioned application to Pym includes in its organization a support for a last with a shoe thereon, a roll, and means for moving the roll bodily to bring it into engagement with the counter portion of the shoe. One of the objects of the present invention is to provide a machine of more simple construction wherein the driving mechanism which rotates the roll is not required to accommodate any bodily movements of the roll. In accordance with this object, one feature of the present invention consists in the provision of means for moving the last support to bring the counter portion of the shoe into engagement with the roll.

Another object of the invention is to prevent such undue wear of the roll, or other member having a shoe-engaging surface, as might occur if the engagements between the shoes and the member always take place at the same portion of the shoe-engaging surface thereof. With a view to preventing such localized wear, another feature of the invention consists in the provision of means for causing engagements between successive shoes and different portions of the shoe-engaging surface, respectively. In the illustrated machine the means for causing engagement with successive shoes to take place at different portions of the shoe-engaging surface is actuated automatically by the means for causing relative movement of approach and of separation between the last support and the shoe-engaging member or

roll, and the direction of the relative movement which causes successive shoes to engage different portions of the shoe-engaging surface is transversely of the shoe and axially or lengthwise of the roll.

In cases where the machine is to be employed as a last pulling machine, it is desirable to make some provision for holding the last upon the last pin against the action of the member which engages and moves the shoe. Accordingly, another feature of the invention consists in the provision of means which not only acts upon the last pin to urge the shoe against the surface of the member, but which also at the same time tends to urge the last on the last pin. Where the member which acts upon the shoe is a roll, this result is accomplished by providing such an inclination between the direction of the last pin and the line of thrust between the last and the roll as to tend to hold the last from slipping from the last pin. Provision is also made for adjusting the position of the last pin support toward and from the roll without varying this inclination of the last pin.

The above and other features of the invention, including details of construction and the arrangement of the actuating mechanism, will now be more particularly described with reference to the accompanying drawings, in which

Fig. 1 is a side elevation of a last pulling machine embodying the invention in a preferred form;

Fig. 2 is a front elevation of the machine illustrated in Fig. 1;

Fig. 3 is a detail sectional view taken on the line III-III of Fig. 1;

Fig. 4 is a sectional view in elevation taken on the line IV-IV of Fig. 2;

Fig. 5 is a sectional view taken on the line V-V of Fig. 1;

Fig. 6 is a view, partly in section, showing the parts illustrated in Fig. 5; and

Fig. 7 is a detail view illustrating the removal of a shoe from its last by the machine.

In the illustrated machine for separating shoes and lasts, the machine comprises a hollow frame 10 which encloses mechanism 100

later to be described. A roll 12 (Fig. 2) of rubber or rubber composition is carried by a horizontal shaft 14 which is journaled in bearings 16 secured to the upper portion notched portion to bind against the sleeve 58 and thereby securely clamp the sleeve 60 to the sleeve 58 in any desired position. *This clamp . . . . .*

1981 to be described in the following section. The 28 figures are grouped into two sets, (E) and (F), and are numbered 1 to 28. The first set, (E), consists of 14 figures, and the second set, (F), consists of 14 figures. The figures are arranged in a sequence, and the sequence is as follows: (E) 1, (E) 2, (E) 3, (E) 4, (E) 5, (E) 6, (E) 7, (E) 8, (E) 9, (E) 10, (E) 11, (E) 12, (E) 13, (E) 14, (F) 1, (F) 2, (F) 3, (F) 4, (F) 5, (F) 6, (F) 7, (F) 8, (F) 9, (F) 10, (F) 11, (F) 12, (F) 13, (F) 14.

tending into a slot 88 formed in the rod 74.

Provision is made for swinging the lever 70 inwardly toward the roll 12. To this end a portion of the lever 70, in the form of an arm 90 (Fig. 4) extends inwardly through an opening 91 in the wall of the frame 10. A stud 92 forming, in effect, an extension of the arm 90 is carried upon the inner end of the arm 90. The arm 90 is so designed and the stud 92 is so secured to the arm 90 as to make the stud 92 coaxial with the sleeve 60 when the lever 70 is in position for the shoe to engage the central portion of the roll 12. A forwardly extending treadle 94 is fulcrumed upon a shaft 96 carried at the rear portion of the base of the frame 10. A coil spring 98 having one end secured to a forward portion of the treadle 94 and the other end secured to an eye which is fixed on the frame, tends to hold the treadle 94 in its uppermost position. A rod 100 is pivotally secured at its lower end to a forward portion of the treadle 94 and at its upper end to a lever 102 which is fulcrumed at 104 to the upper portion of the rear wall of the frame 10 and extends forwardly. A link 106 has a forked end which is trunnioned to a sleeve rotatably carried upon the stud 92, the other end of the link 106 being likewise forked and being similarly connected, by means of a stud, a sleeve and a trunnion, to the lever 102. The link 106 is thus universally pivoted at its ends to the lever 70 and the lever 102, respectively. It is apparent that depression of the treadle 94 against the tension of the spring 98 will pull down the rod 100, rotating the lever 102 in a counterclockwise direction as viewed in Fig. 4, thereby depressing the rod 106 and swinging the lever 70 in a clockwise direction. The rod 100 is made adjustable lengthwise by forming it in two parts which slide lengthwise of each other and which may be clamped in any given position by means of a clamping block 108.

Provision is made for automatically shifting the position of the lever 70 longitudinally of the roll 12 for each inward movement of the lever 70 to prevent the wearing of a groove in the central portion of the roll 12 and to distribute the wear over the entire roll. To this end, a slot 110 (Fig. 4) extending lengthwise of the lever 70 is formed in the intermediate portion of the lever 70. An opening 112 is formed in the front wall of the frame 10 adjacent to the slot 110 and a bracket 114 forming a cover plate for the opening 112 is bolted to the front wall of the frame 10 at this point. The bracket 114 is formed to provide a bearing for a stub shaft 116 which extends horizontally through the bracket 114 from the interior space enclosed by the frame 10 to the outside of the

bracket 114. A short crank 118 (Figs. 5 and 6) is mounted upon the outer end of the shaft 116 and carries an eccentric pin 120 which extends loosely into the slot 110. The crank 118 is secured to the shaft 116 and eccentric pin 120 by means of bill binders 122 of the type previously described. The inner end of the shaft 116 carries a worm wheel 124. For driving the worm wheel 124 a worm 126 is carried on a shaft 128 journaled in an inwardly extending portion of the bracket 114. A ratchet wheel 130 fixed upon the hub of the worm 126 is rotated by the downward movement of the rod 100. To this end a pawl lever 132 is loosely mounted upon the hub of the worm 126 and carries a pivotally mounted pawl 134. A second pawl 136 also engages the ratchet wheel 130 and is pivotally mounted at 137 upon an extension of the bracket 114. The two pawls 134 and 136 are held toward each other and in engagement with the ratchet wheel 130 by means of a tension spring 138. The pawl lever 132 is urged in a counterclockwise direction, as viewed in Fig. 6, by a tension spring 140 one end of which is secured to the pawl lever and the other end of which is secured to a pin 142 which extends horizontally from an extension of the bracket 114. The pin 142 serves also as a stop for the pawl lever 132 against the action of the spring 140. A block 144, which is slidably clamped for purposes of adjustment about the rod 100, engages the pawl lever 132 but clears the end of the pin 142 so that upward movement of the rod 100 will rotate the pawl lever 132 and therefore urge the wheel 130, through the pawl 134, in a clockwise direction as viewed in Fig. 6.

Upon depression of the rod 100 the pawl lever 132 will be rotated in a counterclockwise direction, as viewed in Fig. 6, by the spring 140 as far as permitted by the pin 142, while the pawl 134 will ride over the teeth of the ratchet wheel 130 and the pawl 136 will hold the ratchet wheel 130 from rotation. For each upward movement of the treadle 94 under the influence of the spring 98, the ratchet wheel 130 will therefore be urged through a definite distance and, through the gears 126 and 124, the shaft 116 and the crank 118, the crank pin 120 will be rotated. Such rotation of the crank pin 120, acting upon the side of the wall 110, will cause a swinging movement of the lever 70 longitudinally of the roll 12. A stop pin 146 limits upward movement of the block 144 and thus determines the outward position of the lever 70. A stop member 148 in the form of a sector pivoted to the forward lower portion of the frame 10 may be swung down to engage the treadle 94 directly. In this case, the stop member 148

is employed independently and in place of the stop pin 146.

Mounted upon the upper portion of the frame 10 and adjacent to the roll 12 is a support for a cutting tool comprising a fixed knife 150 (Fig. 1) for cutting the laces of shoes and a guard 152 for protecting the shoes from the knife 150. Similarly mounted upon the upper portion of the frame 10 is a stationary pin 154 over which the operator may force the hole of the instep block of a block last to release the instep block.

In Fig. 7 is shown a shoe S in the process of removal from a last L. While the shoe S is illustrated in Figs. 4 and 7 as having a heel H, thereby indicating that the shoe is substantially complete, it is to be understood that the application of the machine is not limited to the separation of completed shoes from their lasts. On the contrary, the machine serves equally well to separate shoes from their lasts at an early stage of their manufacture. It will be observed that the last pin 72, when holding the last L in position for the shoe S to engage the roll 12, is inclined toward the plane of tangency, indicated by the line T—T on Fig. 7, of the shoe S and the roll 12. That is, the free end of the pin 72 is closer to this plane of tangency T—T than the end which is secured to the lever 70. The purpose of this inclination is to prevent the upward force of the rotating roll upon the shoe from lifting the last from the pin 72. As the shoe is urged against the roll 12, the thrust of the roll 12 endwise of the shoe and of the last will be exerted in a direction normal to the plane of tangency T—T and will tend to force the last downwardly on the pin 72, because of the inclination of the last pin 72 to the line of thrust referred to. As illustrated, the angle of inclination between the last pin 72 and the plane of tangency of the shoe and the roll is about 5 degrees, this particular magnitude having been determined by experiment as desirable.

Owing to the variation in the size of and shape of shoes, the distance between the last pin hole and the rear end of the shoe will vary for different shoes. It is therefore desirable to provide an adjustment for the fulcrum of the lever 70 which will permit the lever 70 to be moved toward or from the roll 12 while maintaining the lever 70 parallel to its former position, that is, without varying the angular position of the lever 70 about the trunnion pins 68, so that the last pin 72 will always incline toward the plane of tangency of the shoe and the roll at an angle of approximately 5 degrees when the shoe is in engagement with the roll. To this end the sleeve 60 may be adjusted, by loosening the bill binder previously described, outwardly on the sleeve

58 to accommodate shoes wherein the distance between the last pin hole and the heel end of the shoe is relatively great, and likewise the sleeve 60 may be adjusted inwardly for shoes wherein this distance is relatively small. This adjustment also enables the operator to take up any wear in the roll by adjusting the sleeve 60 inwardly to accommodate the reduced diameter of the roll.

It is further desirable, for the reasons stated in the preceding paragraph, that the line of adjustment of the fulcrum of the lever 70, or in other words the common axes

75 of the sleeves 60 and 58 and of the stud 56, be parallel to the direction of movement of the heel end of the shoe at the instant of engagement of the shoe with the roll 12 as the lever 70 is swung toward or from shoe engaging position. If the line of ad-

80 justment were otherwise than parallel to this direction of movement of the shoe, the point of tangency of the shoe and the roll would vary, and the angular relation be-

85 tween the last pin 72 and the plane of tan-

90 gency T—T would also vary. It is ap-

95 parent that if, when a shoe is in engagement with the roll 12, the axis of the trunnions 68 be positioned in a plane normal to the axis

99 of the sleeve 60 and passing through the point of contact between the shoe and the roll, then the swinging movement of the end of the shoe toward and from the roll will necessarily be parallel to the axis of the sleeve 60. The lever 70 is therefore de-

100 signed to satisfy this condition for shoes wherein the distance between the last pin hole and the end of the shoe is of average amount. In the case of a shoe wherein this distance is greater than the average, it is necessary, in order to maintain the five de-

105 gree inclination of that last pin, to adjust the sleeve 60 outwardly, so that the trunnions 68 will be positioned outwardly of the desired point, and in the case of shoes wherein this distance is less than the aver-

110 age, the sleeve 60 must be adjusted inwardly and the trunnions 68 will be positioned inwardly of the desired point; but the effect

115 of such departure of the position of the trunnions 68 upon the path of movement of the shoe, and therefore upon the position of the point of tangency of the shoe with the roll, will be so exceedingly slight as to be negligible.

120 The thrust developed between the roll 12 and the shoe S will be a maximum when the plane of tangency T—T is normal to the direction of movement of the heel end of the shoe at the instant of engagement between the shoe and the roll. Provision is therefore made to insure that the plane T—T will be normal to this direction of movement; and since this direction of movement of the heel end of the shoe is, as stated in the preceding paragraph, parallel to the

axis of the sleeve 60, the plane T—T should be normal to the axis of the sleeve 60.

The design of the lever 70 is determined by the above considerations. As previously stated, the stud 92 is coaxial with the sleeve 60 when the shoe is in position to engage the central portion of the roll 12, that is, with the lever 70, as viewed in Fig. 2, in upright position. Since the last pin 72 is

10 inclined at an angle of about 5 degrees to a plane normal to the axis of the sleeve 60, for the same position of the lever 70, it follows that the angle between the axes of the last pin 72 and the stud 92, respectively, is about 15 85 degrees, this angle being the same whatever may be the angular position of the lever 70, since the last pin 72 and the stud 92 are, in effect, portions of the lever 70.

20 The location of the axis of the trunnions 68 will be determined by the intersection of the axis of the stud 92 with a plane normal to the axis of the stud 92 and tangent to the heel end of an average shoe on a last on the pin 72. The length of the lever 70 is

25 determined by the distance of the stud 56 from the roll 12, the lever 70 being of such length that when a last L for a shoe S of average height and having a thimble hole of average depth is mounted on the last pin 70, the heel end of the shoe S on the last will engage the roll 12 at such a point as to make the plane of tangency T—T between the shoe and the roll normal to the axis of the sleeve 60. The previously described

35 heightwise adjustment of the last pin 72 by the knurled head 82 enables the operator to accommodate lasts for shoes of various heights and having thimble holes of various depths without varying the above-described 40 point of engagement, and therefore without varying the plane of tangency T—T.

For convenience, as previously stated, the stud 56 is horizontal. The plane of tangency of the shoe and the roll is therefore vertical,

45 and the last pin, when the shoe is in roll engaging position, is inclined toward the roll at an angle of about 5 degrees from the vertical. The link 106 is so arranged as to be vertical when the stud 92 is coaxial with

50 the sleeve 60, and when the latter is adjusted on the sleeve 58 for an average shoe.

Adjustment of the sleeve 60 in or out for a shoe other than average may thus swing the link 106 about its upper pivot without sub-

55 stantly varying the position of the lever 102 or of the treadle 94. In other words,

the lever 70 may be adjusted toward or from the roll 12 independently of the treadle 94, the rod 100, the lever 102 and the link 106.

60 Adjustment of the sleeve 60 in or out on the sleeve 58 will also vary the normal or clearance position of the lever 70 as determined by the block 144 or the stop 148 independently of the means for swinging the

65 axis of the sleeve 60, the plane T—T should be normal to the axis of the sleeve 60. Furthermore, the above-described movements of adjustment of the lever 70 longitudinally of the roll will merely swing the 70 link 106 about its upper pivot without substantially affecting the lever 102 or the treadle mechanism.

75 In operation, assuming the machine to have been adjusted to the requirements of the particular type of shoe S and the motor 20 to have been started to rotate the roll 12, a lasted shoe is first presented in upright position, as shown in dotted lines in Fig. 1, to bring the lacing into cutting engagement with the knife 152. If the last is of the type having an instep block, the latter is removed by the aid of the pin 154. The last is then placed in inverted position upon the pin 72 with the heel of the shoe extending toward the roll 12. The operator then depresses the treadle 94 to bring the heel end of the shoe firmly into engagement with the surface of the roll 12, and the rotation of the roll 12 causes the counter portion of the 80 shoe to be drawn heightwise off the last. Sufficient friction is developed between the shoe and the roll 12 to prevent any substantial slip between the shoe and the roll. Where a two-part last is employed, the stiffness of the shoe as the latter is tilted assists the operator in breaking the last. The operator then releases the treadle 94 and takes the shoe from the last. The upward movement of the treadle rod 100, upon release of the treadle 94, rotates the crank pin 120 through the pawl and ratchet mechanism above described, thus shifting the lever 70 to a new position longitudinally of the roll 12. The link 106, being universally pivoted 85

90 at each end, will yield sidewise to accommodate this sidewise movement of the lever 70 without appreciably affecting the treadle mechanism. Upon each repetition of the above-described operation, each succeeding 100 shoe will engage a different portion of the surface of the roll 12 from that engaged by its predecessor.

105 Having thus described our invention, what we claim as new and desire to secure by Letters Patent of the United States is:

1. A machine for operating on shoes comprising a support for a last with a shoe thereon, a roll, means for moving said last support to bring the counter portion of the 110 shoe into engagement with said roll, and means for rotating said roll to effect relative movement between the shoe and the last.

120 2. A machine for operating on shoes comprising a support for a last with a shoe thereon, a roll, said support being mounted for pivotal movement toward and from said roll, means for moving said last support toward said roll to bring the counter portion 125 130

of the shoe into engagement with said roll, and means for rotating said roll in a direction to separate the shoe from the last.

3. A machine for separating shoes from lasts having, in combination, a support having a last pin to be received in the thimble hole of a last having a shoe thereon, a roll, means for moving said support to bring the counter portion of a shoe mounted on a last 10 carried by the last pin of the support into engagement with the roll, and gearing for rotating the roll to separate the shoe and the last.

4. A machine for separating shoes and lasts having, in combination, a support provided with an upwardly extending last pin constructed and arranged to be received in the thimble hole of a last having a shoe thereon, a roll, means for moving said support to bring the counter portion of a shoe mounted on a last carried by the last pin of the support into engagement with the roll, and gearing for rotating the roll to separate the shoe from the last.

5. A machine for separating shoes from lasts having, in combination, a support having a last pin to be received in the thimble hole of a last having a shoe thereon, a roll, a treadle, connections between the treadle, 30 and the support so arranged that displacement of the treadle moves the support, thereby bringing the counter portion of a shoe mounted on a last carried by the last pin of the support into engagement with the roll, and gearing for rotating the roll to separate the shoe and the last.

6. A machine for separating shoes from lasts having, in combination, a support provided with an upwardly extending last pin 40 constructed and arranged to be received in the thimble hole of a last having a shoe thereon, a roll, means for moving said support to bring the counter portion of a shoe mounted on a last carried by the last pin of the support into engagement with the roll, gearing for rotating the roll to separate the shoe and the last, and gearing constructed and arranged to cause relative movement of the work support and the roll in a manner 50 such that successive shoes presented to the machine will engage different portions of the surface of the roll.

7. A machine for separating shoes from lasts having, in combination, a support having a last pin to be received in the thimble hole of a last having a shoe thereon, a roll, means for causing relative movement of said support and the roll to bring the counter portion of a shoe mounted on a last carried 60 by the last pin of the support into engagement with the roll, gearing for rotating the roll to separate the shoe and the last, and gearing for causing relative movement of the shoe and the roll in a direction substantially parallel to the axis of the roll, there-

by causing successive shoes presented to the machine to engage different portions of the surface of the roll.

8. A machine for effecting relative movement between lasts and shoes, comprising a support for a last with a shoe thereon, and a member having a frictional shoe-engaging surface and operable by engagement with the shoe to effect relative movement between the shoe and the last, said last support being movable in a direction to enable engagement between successive shoes and said member to take place at different portions, respectively, of the surface of said member.

9. A machine for effecting relative movement between lasts and shoes, comprising a support for a last with a shoe thereon, a member having a frictional shoe-engaging surface and operable by engagement with the shoe to effect relative movement between the shoe and the last, and means for mounting said last support for universal pivotal movement to enable said support to be swung toward said member to effect engagements between successive shoes and said member at different portions, respectively, of the surface of said member.

10. A machine for effecting relative movement between lasts and shoes, comprising a support for a last with a shoe thereon, and a driven roll operable by frictional engagement with the shoe to effect relative movement between the shoe and the last, said last support being movable in a direction to enable engagement between successive shoes and said roll to take place at different positions, respectively, along the length of said roll.

11. A machine for effecting relative movement between lasts and shoes having, in combination, a support for a last with a shoe thereon, and a driven roll operable by frictional engagement with the shoe to effect relative movement between the shoe and the last, said last support being movable toward said roll to effect engagement between the shoe and the roll, said last support being movable also axially of said roll to enable engagement between successive shoes and said roll to take place at different positions, respectively, along the length of said roll.

12. A machine for operating on shoes comprising a support for a last with a shoe thereon, means having a shoe-engaging surface and operable by engagement with a shoe on a last on said last support to effect relative movement between the shoe and the last, and means for causing engagements between successive shoes and different portions of said shoe-engaging surface respectively.

13. A machine for operating on shoes comprising a member having a shoe-engaging surface, a support for a last with a shoe thereon, means for causing relative move-

- ments between said last support and said member to effect engagements between successive shoes and different portions of said shoe-engaging surface respectively, and
 5 means for causing relative movement between said last support and said member during the engagement between each shoe and said member to effect relative movement between each shoe and its last.
- 10 14. A machine for operating on shoes comprising a member having a shoe engaging surface, a support for a last with a shoe thereon, means for causing relative movements of approach and of separation between said last support and said member, said movement of approach serving to effect engagements between successive shoes and said member, means associated with said relative-movement-causing means for causing
 15 said engagements of successive shoes to take place at different portions of said surface respectively, and means for causing relative movement between said last support and said member during the engagement between each shoe and said member to effect relative movement between each shoe and its last.
- 20 15. A machine for operating on shoes comprising a member having a shoe-engaging surface, a support for a last with a shoe thereon, means for causing relative movements between said last support and said member to effect engagements between successive shoes and said member, means for causing relative movement between said last support and said member during the engagement between the heel end
 25 of each shoe and said member to effect relative movement between each shoe and its last in a direction heightwise of the shoe, and means for causing relative movements transversely of the shoes and between said last support and said member to vary respectively the successive portions of said shoe engaging surface at which engagements with successive shoes are effected.
- 30 16. A machine for operating on shoes comprising a member having a shoe-engaging surface, a support for a last with a shoe thereon, means for causing relative movements between said last support and said member to effect engagements between successive shoes and said member, means for causing relative movement between said last support and said member during the engagement between each shoe and said member to effect relative movement between each shoe and its last, and means for causing other relative movements between said last support and said member to vary respectively the successive portions of said shoe-engaging surface at which engagements with successive shoes are effected.
- 35 17. A machine for operating on shoes comprising a member having a shoe-engaging surface, a support for a last with a shoe thereon, means for causing relative movements of approach and of separation between said last support and said member, said movements of approach serving to effect engagements between successive shoes and said member, means for causing relative movement between said last support and said member during the engagement between each shoe and said member to effect relative movement between each shoe and its last, and means for moving said last support to insure that the engagements of successive shoes with said member shall take place respectively at different portions of the shoe-engaging surface of said member.
- 40 18. A machine for operating on shoes comprising a member having a shoe-engaging surface, a support for a last with a shoe thereon, means for causing relative movements between said last support and said member to effect engagements between successive shoes and said member, means for causing relative movement between said last support and said member during the engagement between each shoe and said member to effect relative movement between each shoe and its last in a direction heightwise of the shoe, and means for causing relative movements transversely of the shoes and between said last support and said member to vary respectively the successive portions of said shoe engaging surface at which engagements with successive shoes are effected.
- 45 19. A machine for operating on shoes comprising a member having a shoe-engaging surface, a support for a last with a shoe thereon, means for causing relative movements between said last support and said member to effect engagements between successive shoes and said member, means for causing relative movement between said last support and said member during the engagement between each shoe and said member to effect relative movement between each shoe and its last, and means for moving said last support to insure that the engagements of successive shoes with said member shall take place respectively at different portions of the shoe-engaging surface of said member.
- 50 20. A machine for operating on shoes comprising a member having a shoe-engaging surface, a support for a last with a shoe thereon, means for causing relative movements between said last support and said member to effect engagements between successive shoes and said member, means for causing relative movement between said last support and said member during the engagement between each shoe and said member to effect relative movement between each shoe and its last, and means for moving said last support transversely to the direction of the movements caused by the first said means.

to insure that the engagements of successive shoes with said member shall take place respectively at different portions of the shoe-engaging surface of said member.

5 21. A machine for operating on shoes comprising a rotary member having a shoe-engaging surface, a support for a last with a shoe thereon, means for causing relative movements between said last support and said member to effect engagements between successive shoes and said member, means for rotating said member during the engagement between each shoe and said member to effect relative movement between each shoe and 10 its respective last, and means for moving said last support to insure that the engagements of successive shoes with said member shall take place respectively at different portions of the shoe-engaging surface of said 15 member.

22. A machine for separating shoes and lasts, comprising a roll, a support for a last with a shoe thereon, means for causing relative movements between said last support and said roll to effect engagements between successive shoes and said roll, means for rotating said roll in a direction to separate each shoe from its last, and means for moving said last support to insure that the engagements of successive shoes with said roll shall take place respectively at different portions of the shoe-engaging surface of said 20 roll.

23. A machine for separating shoes and lasts, comprising a roll, a support for a last with a shoe thereon mounted for movement toward and from said roll and also for movement lengthwise of said roll, means for moving said last support toward said roll 35 to bring a shoe on its last into engagement with said roll, means for rotating said roll in a direction to separate the shoe from the last, and means for moving said last support lengthwise of said roll to insure that the engagements of successive shoes with said roll shall take place respectively at different portions of the shoe-engaging surface of said roll.

24. A machine for separating shoes and lasts, comprising a roll, a support for a last with a shoe thereon, means for causing relative movements of approach and of separation between said last support and said roll, said movements of approach serving to effect engagements between successive shoes and said roll, means for rotating said roll in a direction to separate each shoe from its last, and means actuated by the first said means for moving said last support in a direction to insure that the engagements of successive shoes with said roll shall take place respectively at different portions of the shoe-engaging surface of said roll.

25. A machine for separating shoes and lasts, comprising a member having a shoe-

engaging surface, a support for a last with a shoe thereon, means including a universal pivot for supporting said last support to permit movements thereof toward said member to bring successive shoes into engagement with said member and also to permit movements of said last support in a direction to insure that the engagements of successive shoes with said friction member shall take place respectively at different portions of the shoe-engaging surface of said member, and means for effecting relative movement between said last support and said member in a direction to separate each shoe and its last.

70 26. A machine for separating shoes and lasts, comprising a movably mounted member having a shoe-engaging surface, a universally pivoted support for a last with a shoe thereon, means for moving said last support toward said member to bring the shoe on the last into engagement with a portion of the shoe-engaging surface of said member, means for moving said member in a direction to separate the shoe from the last, and means for moving said last support in a direction to insure that a succeeding shoe on its last, when the last support is again moved toward said member, shall engage a different portion of the shoe-engaging surface of said member.

75 27. A machine for separating shoes and lasts, comprising a movably mounted member having a shoe-engaging surface, a universally pivoted support for a last with a shoe thereon, means for moving said last support toward said member to bring the shoe on the last into engagement with a portion of said shoe-engaging surface and for moving said last support away from said member, means for moving said member in a direction to separate the shoe from the last, and means for moving said last support in a direction to insure that a succeeding shoe on its last, when said last support is again moved toward said member, will engage a different portion of said shoe-engaging surface, the second said means for moving said last support being actuated by the first said means for moving said last support.

80 28. A machine for separating shoes and lasts, comprising a movably mounted member having a shoe-engaging surface, a universally pivoted lever adapted to carry a last with a shoe thereon, means for actuating said lever to move said lever toward said member to bring the shoe on the last into engagement with a portion of said shoe-engaging surface and to retract said lever from said friction member, means for moving said member to separate the shoe from the last, and means connected with said actu-

- ating means for successively varying the path of movement of said lever toward said member to insure that each succeeding shoe on its last will engage a different portion 5 of the surface of said member.
29. A machine for separating shoes and lasts, comprising a movably mounted member having a shoe-engaging surface, a universally pivoted lever adapted to carry a last with a shoe thereon and having a longitudinally extending slot, means for actuating said lever to move it toward said member to bring the shoe on the last into engagement with a portion of said shoe-engaging 10 surface, means for moving said member to separate the shoe from the last, a rotary member carrying an eccentric pin, said pin extending into said slot, and the axis of said rotary member extending in the direction 15 of movement of said lever toward and from said member, and means for rotating said rotary member to vary each succeeding path of movement of said lever toward said member, thereby to insure that each succeeding shoe will engage respectively a different portion of the shoe-engaging surface of said member.
30. A machine for separating shoes and lasts, comprising a roll having a shoe-engaging 20 surface, a universally pivoted lever adapted to carry a last with a shoe thereon, said lever having a slot, means for actuating said lever to move said lever toward said roll to bring the shoe on the last into engagement with a portion of said shoe-engaging surface, means for rotating said roll in a direction to separate the shoe from the last, a rotary member carrying an eccentric pin, 25 said eccentric pin engaging said slot of said lever, and said slot and said rotary member being relatively disposed to cause movement of said lever lengthwise of said roll upon rotation of said rotary member, and means for rotating said rotary member to shift said lever lengthwise of said roll thereby to insure that each succeeding shoe on its last shall engage a different portion of said surface for each succeeding movement of said 30 lever toward said roll.
31. A machine for separating shoes and lasts, comprising a roll having a shoe-engaging 45 surface, a universally pivoted lever adapted to carry a last with a shoe thereon, said lever having a slot, means for actuating said lever to move said lever toward said roll to bring the shoe on the last into engagement with said shoe-engaging surface, means for rotating said roll in a direction 50 to separate the shoe from the last, a rotary member carrying a ratchet and an eccentric pin, said eccentric pin engaging said slot of said lever, and said slot and said pin being relatively disposed to cause movement 55 of said lever lengthwise of said roll upon

rotation of said rotary member, and a pawl engaging said ratchet and actuated by said lever actuating means to turn said rotary member, thereby to insure that each succeeding shoe on its last will engage a different 70 portion of said surface upon each succeeding movement of said lever toward said roll.

32. A machine for separating shoes and lasts, comprising a last pin for supporting a last with a shoe thereon, a member having a shoe-engaging surface, means acting upon said last pin to urge the shoe against said shoe-engaging surface while tending to urge said last pin further into the thimble hole of the last, and means for moving said member in a direction to separate the shoe from the last.

33. A machine for separating shoes from lasts, comprising a pin for supporting a last with a shoe thereon, a roll, means acting upon said last pin to urge the heel end of the shoe against said roll to develop a thrust between the last and said roll, said last pin being so inclined to the line of said thrust as to tend to hold the last from slipping therefrom, and means for rotating said roll in a direction to separate the shoe from the last.

34. A machine for separating shoes from lasts, comprising a pin for supporting a last with a shoe thereon, a roll, means for supporting said last pin in a position in which the heel end of the shoe is in engagement with said roll and said last pin 95 is inclined toward the plane of tangency of the shoe with said roll, and means for rotating said roll in a direction to separate the shoe from the last.

35. A machine for separating shoes from lasts, comprising a pin for supporting a last with a shoe thereon, a roll, means for supporting said last pin in a position wherein the heel end of the shoe is in engagement 105 with said roll and said last pin is inclined at an angle of substantially five degrees toward the plane of tangency of the shoe with said roll, and means for rotating said roll in a direction to separate the shoe from the last.

36. A machine for separating shoes from lasts, comprising a pin for supporting a last with a shoe thereon, a roll, means for supporting the last pin in a position wherein the heel end of the shoe is in engagement with said roll and said last pin is inclined toward the plane of tangency of the shoe and said roll, said last pin supporting means being adjustable 120 to vary said position of said last pin toward and from said roll to accommodate shoes of varying type without varying the inclination of said last pin, and means for rotating said roll in a direction to separate the shoe from the last.

37. A machine for separating shoes from lasts, comprising a lever carrying a pin for supporting a last with a shoe thereon, a member having a shoe-engaging surface, a pivotal support for said lever, means for swinging said lever about said pivotal support to cause the shoe to engage said surface of said member, and means for effecting relative movement between said lever and said member in a direction to separate the shoe from the last, said pivotal support being adjustable to vary the position of said lever toward and from said member.

38. A machine for separating shoes and lasts, comprising a lever carrying a pin for supporting a last with a shoe thereon, a member having a shoe-engaging surface, a pivotal support for said lever, means for urging said lever about said pivotal support to cause the heel end of the shoe to press against said surface of said member, said lever, said last pin and said pivotal support being constructed and arranged to maintain said last pin inclined at a definite angle toward the plane of tangency of the shoe and said surface, such inclination being for the purpose of holding the last on said last pin, and means for effecting relative movement between said lever and said member to separate the shoe from the last, said pivotal support being adjustable to insure that said last pin shall be inclined at the same definite angle toward the plane of tangency of a shoe of different type and said surface of said member.

39. A machine for separating shoes and lasts, comprising a member having a shoe-engaging surface, a support for a last with a shoe thereon, means including a pivot for supporting said last support, means for moving said last support toward said member to bring the shoe on the last into engagement with said surface of said member, and means for causing relative movement between said last support and said member to separate the shoe from the last, said supporting means being adjustable upon said pivot to vary the distance between said last support and said member independently of said last support moving member.

40. A machine for separating shoes and lasts, comprising a member having a shoe-engaging surface, a support for a last with a shoe thereon, a pivotal support for said last support, means cooperating with said pivotal support for normally holding said last support in an initial position away from said member, means for moving said last support toward said member to bring the shoe on the last into engagement with said surface of said member, and means for causing relative movement between said last support and said member to separate the shoe from the last, said pivotal support being adjustable to vary the initial position of

said last support toward or from said member.

41. A machine for separating shoes and lasts, comprising a member having a shoe-engaging surface, a support for a last with a shoe thereon, means for normally maintaining a definite distance between said last support and said member, means for causing relative movement between said last support and said member to effect engagement between the shoe on the last and said surface of said member, and means for causing relative movement between said last support and said member to separate the shoe from the last, said last support being adjustable independently of the first said movement-causing means for varying the definite distance normally maintained between said last support and said member.

42. A machine for separating shoes and lasts, comprising a member having a shoe-engaging surface, a support for a last with a shoe thereon, means including a spring for normally maintaining a definite distance between said last support and said member, means for causing relative movement between said last support and said member, to effect engagement between the shoe on the last and said surface of said member, and means for causing relative movement between said last support and said member to separate the shoe from the last, said last support and the first-named means for causing relative movement being constructed and arranged to permit adjustment of said last support without varying the length of said spring to vary the definite distance normally maintained between said last support and said member.

43. A machine for separating shoes and lasts, comprising a member having a shoe-engaging surface, a support for a last with a shoe thereon, means including a stop for normally maintaining a definite distance between said last support and said member, means for causing relative movement between said last support and said member to effect engagement between the shoe on the last and said surface of said member, and means for causing relative movement between said last support and said member, to separate the shoe from the last, said last support and the first-named means for causing relative movement being constructed and arranged to permit adjustment of said stop to vary the definite distance normally maintained between said last support and said member.

44. A machine for separating shoes and lasts, comprising a member having a shoe-engaging surface, a lever constructed and arranged to support a last with a shoe thereon, a pivotal support for said lever, means

for swinging said lever about said pivotal support to bring the shoe into engagement with said surface of said member, and means for effecting relative movement between 5 said lever and said member in a direction to separate the shoe from the last, said pivotal support being adjustable to shift said lever toward and from said member while maintaining said lever parallel to its former 10 position.

45. A machine for separating shoes and lasts, comprising a member adapted to engage a shoe tangentially, a lever constructed and arranged to support a last with a shoe 15 thereon, a pivotal support for said lever, means for swinging said lever about said pivotal support to bring the shoe into engagement with said member, and means for effecting relative movement between said 20 lever and said member in a direction to separate the shoe from the last, said pivotal support being adjustable in a line substantially parallel to the direction of movement, as the shoe engages said member, of the point 25 of the shoe which tangentially engages said member.

46. A machine for effecting relative movement between shoes and their respective lasts, comprising a pin for supporting a last 30 with a shoe thereon, a support for said pin, a member having a shoe-engaging surface, means for effecting engagement between the shoe and said surface of said member, and means for causing relative movement between said last pin support and said member in a direction to effect relative movement between the shoe and the last, and means 35 geared to said last pin for adjusting said last pin in a direction heightwise of the shoe.

40 47. A machine for separating shoes and lasts, comprising a pin for supporting a last with a shoe thereon, a support for said pin, a member having a shoe-engaging surface, means for effecting engagement between the 45 shoe and said surface of said member, means for causing relative movement between said last pin support and said member in a direction to separate the shoe and the last, and means including a rack and pinion for adjusting said last pin in said last pin support 50 in a direction heightwise of the shoe.

48. A machine for separating shoes and lasts, comprising a pin for supporting a last 5 with a shoe thereon, said pin having rack teeth formed upon it, a support for said pin, a roll, means for effecting engagement between the shoe and said roll, means for rotating said roll in a direction to separate the shoe from the last, a pinion journaled in said support and engaging said rack teeth, means for rotating said pinion to effect adjustment of said last pin in a direction heightwise of the shoe to determine 35 the point on the shoe which can engage the

roll, and means for locking said rotating means in adjusted position.

In testimony whereof we have signed our names to this specification.

JOHN M. WHELTON. 70
